SEWING MACHINE ATTACHMENT

Filed May 28, 1928

UNITED STATES PATENT OFFICE.

JOHN B. RANSOM, OF TROY, NEW YORK.

SEWING-MACHINE ATTACHMENT.

Application filed May 28, 1928. Serial No. 281,128.

The present invention relates to attachments for sewing machines or the like, and more particularly for machines of the type adapted to "tack" or sew a length of tape or the like to a garment.

In the manufacture of certain types of garments, particularly trunks, it is customary to sew to the inner face of the waist band a length of tape, the ends of which are, after the sewing operation, threaded or drawn through holes or openings to the outer face of the band. The tape is provided for the purpose of varying the length of the waist band, which is accomplished by tying together the ends of the tape which project through the openings.

Heretofore, in attaching these tapes, several lengths of which are ordinarily associated with a waist band, it has been customary first to sew the same to the inner face of the band, and thereafter the ends of the tape are threaded through the openings, ordinarily by another operator.

An object of the invention is to reduce the labor and consequent expense in manufacture of garments of this type by providing an attachment for a sewing mechanism, which will serve more or less automatically to thread the ends of the tape through the openings in the waist band, and thus eliminate the ordinarily separate or independent threading operation.

The invention contemplates the provision of an attachment for the sewing or "tacking" machine, which may be placed upon the bed of the machine. The attachment comprises, preferably, a base plate having one or more upstanding hooks adapted to project through the holes or openings in the fabric or waist band and to receive therein the tape as it is sewed or "tacked" to the inner face of the band. The hooks are formed so that as they are withdrawn from the openings, preferably by removing the fabric and tape from the bed, they will serve to draw the ends of the tape through the openings. The hooks are preferably adjustable relative to one another, so that their relative positions with respect to one another and with respect to the sewing mechanism, may be varied, and thus they may be properly positioned to project through the holes in the waist band, to which at a predetermined point, preferably intermediate the holes, the tape is to be "tacked".

The invention also contemplates the pro-

vision of means for accurately gauging the length of tape at opposite sides of the point of tacking or sewing.

Referring to the accompanying drawings, 60 wherein there is shown a preferred embodiment,

Figure 1 is a perspective showing the attachment applied to a sewing machine of conventional type, although it will be understood, of course, that in the manufacture of garments, special types of sewing mechanism are employed, differing specifically from that illustrated.

Figure 2 is a top plan view. 70

Figure 3 is an edge view, and

Figure 4 is a sectional view on the line 4—4 of Figure 2.

Referring to the drawings for a detailed description, 10 designates a conventionally illustrated sewing or "tacking" machine, having a bed 11 upon which, beneath the sewing mechanism 12, is arranged a plate 13 having a central opening 14, coinciding with an opening in the bed. The plate may be secured to the bed as by means of screws 15. At opposite sides of the opening 14 and of the sewing mechanism are arranged upstanding members 16 which may be conventionally termed "hooks", although it will be understood by this term, as used throughout the specification and claims, is meant any member adapted to project through openings in a garment, and to receive therein a length of tape or the like for the purpose of drawing the latter through the opening when the hook is withdrawn from said opening.

The hooks 16 have downwardly extending terminals 16' whereby to form substantially closed upper ends 16''. Each hook is arranged upon a relatively flat shank 17, resting upon the plate 13, and slidably secured to an overhanging guide plate 18 having an elongated slot 19 adapted to receive a screw 20, which projects into the shank 17 and serves to secure the shank to the guide 18 at any selected point along the slot 19. As will be understood, by loosening the screw 20, which clamps the shank 17 to its slotted guide 18, the hooks may be adjusted toward and from one another to arrange the same at the proper position to project through the openings in the garment. The guide 18 has a laterally extending portion 21 secured by screw 22 to the plate 13. The screws 22 project through elongated slots 23, so that

the position of the hooks may be adjusted at a right angle to the length of the slot 19.

This arrangement provides two adjustments for each hook, namely (1) lengthwise of the slot 19 or toward and from one another, and (2) lengthwise of slots 23, whereby the hooks are moved in parallelism. From the foregoing description, it will be apparent that after the proper position of the hooks has been selected, and the same have been fixed in position, a piece of fabric such as a garment waist band B' having openings 25 is arranged upon the machine bed with the hooks projected through the openings. A 15 tape T is drawn from a suitable roll or other supply, until its end 26 reaches a gauge lug 27 upon the end of a gauge arm 28, which is adjustably secured to the plate 13 by means of a clamp 29 carrying screws 30 which project through a slot 31 in arm 28 into the plate 13. The slot 31, as will be understood, permits adjustment of the gauge so that the proper length of tape may be determined depending upon the size of the garment, or the 25 nature of the article to which the tape is being attached. When the proper length of tape has been selected, and the point along the same to be tacked to the waist band has been determined, the tape is arranged within 30 the hooks and tacked or sewed, as at 32 (Figure 2) to the inner face of the band.

As will be observed, the hooks are suitably arranged so that the same may hold the tape therein while being sewed to the garment. 35 Obviously, as the garment is raised from the bed to withdraw the hooks from the openings, the hooks will draw the ends of the tape through the openings. The end T' of the tape may be severed from the supply roll 40 either before the sewing operation or thereafter, although, of course, this will be done before the fabric is removed from the bed, so that the free ends of the tape may be drawn through the openings 25. Before 45 severing the end T', the proper point for severance may be determined by folding into coincidence with the same the opposite end T, which has been measured by the gauge 27, and thus the lengths at opposite sides of the 50 point of tacking 32, will be accurately equalized.

Obviously, the invention may be embodied in constructions differing from that illustrated and described in detail, and the essential characteristics of the invention are more clearly indicated in the following claims.

I claim:

1. A sewing machine attachment comprising a plate adapted to be secured to a sewing machine bed, an upstanding hook on said plate adapted to project through an opening in a garment and to receive a tape or the like while the latter is being attached to the gar-

ment, said hook being formed to draw the tape through said opening when the fabric and tape are raised from the plate, and means for adjusting said hook on the plate whereby to vary its position relative to a sewing mechanism.

2. A sewing machine attachment comprising a plate adapted to be associated with a sewing machine bed, a plurality of upstanding hooks on said plate spaced apart, said hooks being adapted to project through openings in a garment on said bed and to receive therein portions of a length of tape while the latter is being sewed to the garment, said hooks having substantially closed upper ends whereby to draw the tape through said openings when the fabric and tape are removed from the bed, and means for adjusting said hooks laterally and relatively to one another.

3. In a sewing machine and in combination with the sewing needle thereof, a bed having a plurality of normally fixed upstanding hooks adapted to project through openings in a garment or the like, the hooks having substantially closed upper ends and being adapted to receive a tape or the like while being sewn to a garment whereby when the garment is removed from the bed the tape may be drawn by the hooks through said openings, said hooks being spaced apart whereby a portion of the tape therebetween may be sewn to a garment.

4. In a sewing machine and in combination with the sewing needle thereof, a bed having a plurality of normally fixed upstanding hooks adapted to project through openings in a garment or the like, means for relatively adjusting said hooks laterally, the hooks having substantially closed upper ends and being adapted to receive a tape or the like while being sewn to a piece of fabric, whereby when the garment is removed from the bed the tape may be drawn by the hooks through said openings, said hooks being spaced apart whereby a portion of the tape therebetween may be sewed to a garment.

5. A sewing machine attachment comprising a plate adapted to be secured to a sewing machine bed, an upstanding hook on said plate adapted to project through an opening in a garment and to receive a tape or the like while the latter is being attached to the fabric, said hook being formed to draw the tape through said opening when the fabric and tape are raised from the plate, and gauge means on said plate for equalizing the length of tape at opposite sides of the point of sewing of the same to the fabric.

In testimony whereof I have hereunto set my hand.

JOHN B. RANSOM.
